UNITED STATES PATENT OFFICE.

JOSEPH TYRA, OF MINNEAPOLIS, MINNESOTA.

SHEET-METAL DOOR.

No. 841,908.

Specification of Letters Patent.

Patented Jan. 22, 1907.

Application filed March 10, 1906. Serial No. 305,269.

To all whom it may concern:

Be it known that I, JOSEPH TYRA, a citizen of the United States, residing at Minneapolis, in the county of Hennepin and State of Minnesota, have invented certain new and useful Improvements in Sheet-Metal Doors; and I do hereby declare the following to be a full, clear, and exact description of the invention, such as will enable others skilled in the art to which it appertains to make and use the same.

My invention relates to sheet-metal doors, and has for its especial object to provide a door of this character that is so constructed or reinforced internally that a person cannot pass therethrough even if the sheet-metal plates of the door be removed or broken away.

To the above ends the invention consists of the novel devices and combinations of devices hereinafter described, and defined in the claims.

The invention is illustrated in the accompanying drawings, wherein like characters indicate like parts throughout the several views.

Referring to the drawings, Figure 1 is a view in elevation, showing a sheet-metal door embodying my invention and showing also a door-frame in which the door is hung, some parts of the door being broken away. Fig. 2 is a horizontal section taken on the line $x^2 x^2$ of Fig. 1. Fig. 3 is a view corresponding to Fig. 1, but illustrating a modified construction; and Fig. 4 is a horizontal section taken on the line $x^4 x^4$ of Fig. 3.

Referring to the drawings, the numeral 1 indicates the door-frame, which may be of any suitable construction.

The numeral 2 indicates sheet-metal plates that are bent to form the vertical upper, lower, and intermediate stiles of the door, and the numeral 3 indicates metal plates that are bent to form the door-panels.

The numeral 4 indicates metallic strips that are bent to form moldings and which are secured to the plates 2 and to the panel-plates 3 in rectangular arrangement around the four edges of each panel.

Referring now to Figs. 1 and 2, the numeral 5 indicates a marginal rectangular rein-

forcing-frame, which, as shown, is made up of panel-plates connected at the four corners of the frame by angle-plates 6. This rectangular reinforcing-frame 6 is placed within the sheet-metal door and bears against the top and bottom of the door, and thus maintains the form of the door and gives strength thereto.

In accordance with my invention I place a hard-metal barrier within the door between the inner and outer plate portions thereof and arrange the same so that a person cannot pass through the door even when the metal plates of the door are broken or torn off. In Figs. 1 and 2 this barrier is made up of a plurality of parallel rods disposed horizontally one over the other, extended transversely of the door between the inner and outer plates thereof, and riveted at their ends to the vertical bars of the reinforcing-frame 6. These bars 7 will preferably be of hardened or spring tempered steel, so that they cannot be readily broken or sawed. The said rods are of course placed so close together that a person cannot pass between them.

In the construction illustrated in Figs. 3 and 4 the barrier is in the form of an imperforate hard-metal plate 8 of considerable thickness. In this construction the rectangular marginal reinforcing-frame is made up of laterally-spaced pairs of metal angle-bars 9, which are riveted to the four edges of the said plate. Both forms of the barrier greatly strengthen the door in all respects and make it practically impossible for a person to force a passage through the door.

A door of the character above described is desirable for use in a great many different places—such, for instance, as bank-buildings, store-buildings, safety-deposit buildings, and generally wherever great secrecy is desired. They are also desirable for use in jails and other places where persons are to be confined.

What I claim is—

1. A sheet-metal door having a rectangular marginal reinforcing-frame placed therein, and having parallel bars serving as a barrier applied to said marginal frame between the inner and outer plates thereof, substantially as described.

2. A sheet-metal door having a rectangular marginal reinforcing-frame placed therein, and having a metal barrier applied to said marginal frame and extending transversely of the door from the top to the bottom thereof, between the inner and outer plates thereof, substantially as described.

In testimony whereof I affix my signature in presence of two witnesses.

JOSEPH TYRA.
